(57) **CLAIM**

The ornamental design for a head cover, as shown and described.

DESCRIPTION

FIG. 1 is a perspective view of the head cover;
FIG. 2 is another perspective view thereof;
FIG. 3 is a front view thereof;
FIG. 4 is a back view thereof;
FIG. 5 is a top view thereof;
FIG. 6 is a bottom view thereof;
FIG. 7 is a side view thereof; and,
FIG. 8 is an opposite side view thereof.
In the drawings, the broken lines depict stitching and form part of the claimed design.

1 Claim, 4 Drawing Sheets
